TEXTILE PRINT BLANKET

William C. Ross and Stephen B. Nalley, Winches-
ter, Mass., assignors to Dewey and Almy Chemi-
cal Company, North Cambridge, Mass., a cor-
poration of Massachusetts

Application October 24, 1944, Serial No. 560,176

3 Claims. (Cl. 154—54.5)

1

This invention relates to textile printing and is directed to the improvement of wash-blankets.

Among the objects of the invention are to minimize flushing, both at the selvage edge and in the body of the goods, to provide means to prevent color from working under the goods, to make cleaning of the blanket by washing more effective, and to make drying of the blanket more complete.

Figure 1 is a perspective view of one form of our invention.

Figure 2 is a cross section through a portion of the blanket, and

Figure 3 is a perspective view of an alternative construction of our invention.

In printing textiles by the wash-blanket process the color which is left on the roll beyond the selvage of the goods being printed and also whatever surplus color is driven through the goods is carried away on the blanket. In the wash-blanket process great care must be exercised to prevent edge flush, which comes about because the surplus color laid on the blanket is squeezed under the selvage of the goods.

We have discovered that by providing the surface of a printing blanket with a series of minute parallel longitudinal channels the color as it advances before the pressure wave tends to travel along the channel and does not turn laterally to run under the goods, as in the past. As a specific example of a blanket on which a wide variety of patterns and of goods may be printed, we mold fifty channels 10—10 to each inch of width in the working surface 11 of our improved printing blanket 12. These channels are parallel and extend longitudinally of the blanket. Both the channel 10 and the ridge 13 have triangular cross sections, the altitudes of which are ten thousandths of an inch. For reasons which we will later describe we prefer a triangular channel, but we find that it is also possible to make the walls of the channels perpendicular, to form them as concave or convex arcs, or as straight lines at any angle. The dimensions of the channel and the number of the channels may vary since the exact requirements are set by the pattern, the composition of the color, and the weave of the goods. It is important to make each channel large enough so that it will provide a sufficient volume to carry away the surplus color, and it is important to make each channel small enough and to provide a sufficient number of channels to the linear inch so that an image of the individual channel does not appear in the printing. If the channel pattern is too coarse, "bridging" will occur. When a printing

2

blanket possesses a working face molded in this manner, we find that the color deposited in the channel tends to flow parallel with the axis of the blanket instead of flowing laterally, as before. By maintaining the flow of color parallel to the axis of the blanket the color does not work under the selvage and edge flushing is minimized.

Alternatively, the channels may be molded in 10 the working surface of the blanket so that they do not extend exactly parallel with the axis of the blanket, but a herringbone pattern, as illustrated in Figure 3, is produced. The individual channels 10a of the blanket 12a start at the axis 14 of the blanket and have a slight angle of departure so that every channel at some time terminates in the margin of the blanket as illustrated at 15. With such configuration, the color is diverted from the margin of the goods as it is forced along the channels 10a by the pressure wave.

Other advantages follow. We find that, for example, flushing in the body of the goods is greatly minimized. This may be explained because the pressure applied to the blanket by the color roll is applied transversely across a multitude of channel walls. Thus, even under the roll pressure, the channels maintain their dimensions to a substantial degree. In contrast, when a transverse pattern is molded in the surface, the line of pressure applied by the color roll is parallel to the individual margin of the pattern. That margin is crushed, and folds over. The color reservoir which the pattern was intended to produce collapses, and the color on the blanket is displaced, causing flushing. We find, also, that our improved blanket is more effectively washed free of color in the washing part of the apparatus.

40 We prefer the triangular configuration of the channels because we find that the blankets are more thoroughly washed by rotary brushes when the channels have this shape, and we also find that when the channels are triangular, the squeeze roll, which squeezes the wash water off the blanket more effectively dries the blanket.

We claim:

1. The improved blanket for textile printing machines, the printing surface of which is composed of substantially continuous alternating ridges and grooves extending generally lengthwise of the blanket and affording a barrier against transverse travel of the printing color beneath the goods being printed.

50 2. The improved blanket for textile printing

machines, the printing surface of which is composed of substantially continuous alternating ridges and grooves extending parallel with the axis of the blanket and affording a barrier against transverse travel of the printing color beneath the goods being printed.

3. The improved blanket for textile printing machines, the printing surface of which is composed of substantially continuous alternating ridges and grooves extending generally lengthwise of the blanket and at an acute angle to the axis thereof and affording a barrier against transverse travel of the printing color beneath the goods being printed.
